PAPER CARRIAGE FOR ACCOUNTING MACHINES

Walter A. Anderson, Bridgeport, Conn., assignor to Underwood Elliott Fisher Company, New York, N. Y., a corporation of Delaware

Application June 25, 1937, Serial No. 150,367

13 Claims. (Cl. 197—127)

This invention relates to accounting machines, and more particularly to the type having a traveling paper carriage movable laterally for recording in a plurality of columns on a work sheet.

6 Many machines of this character are equipped with what is known as a "front feed" device whereby a work sheet may be fed into the machine by being inserted downwardly from the front of the platen. This type of paper feeding 10 requires that the customary front pressure rolls be moved away from the platen an appreciable distance when the paper is being fed into the machine by the operator. It is therefore necessary to return the pressure rolls into engagement 15 with the platen after the paper is inserted and before the printing mechanism functions.

In the type of machine on which the present invention is shown the pressure rolls are secured to a bail extending across the front of the carriage, and as the bail is moved away from and toward the platen in moving the pressure rolls, this operation will be referred to as "opening and closing the front feed bail."

Since the necessary opening and closing of the 25 front feed bail, when manually operated, places an additional burden on the operator, it is an object of the present invention to provide mechanism capable of doing this work as an incident to routine operation of the machine.

30 A further object of the invention is to provide a mechanism of this character that is simple in construction, adjustable for operation at any desired point in the carriage travel, and which is capable of opening and closing the carriage any 35 desired number of times during each lateral excursion thereof.

With these and incidental objects in view, the invention consists in certain novel features of construction and combinations of parts, the essential elements of which are set forth in appended claims, and a preferred embodiment of which is hereinafter described with reference to the drawings which accompany and form part of the specification.

Detailed description

In the drawings, the accounting machine 1 has a traveling paper carriage 2 with side walls 3 25 and 4. The carriage is movable laterally of the machine on a track 5. A front feed bail 6 extends across the front of the carriage in front of and above a roller platen 1 to accommodate work sheets inserted downwardly into the machine in front of the platen. The bail 6 carries a suitable number of front pressure rolls 8 and is pivoted at 9 (Figure 7) at each side of the carriage for movement forward and rearward of the machine under control of a detent 11 pivoted to the bail at 12. A spring 13 connected to detent 11 and to the frame of the paper carriage holds detent 11 in engagement with a stud 14 on the carriage frame. Two recesses 15 and 16 in detent 11 determine the forward and rearward 30 positions of the bail 6. 35

For further details of the accounting machine and paper carriage reference may be had to the co-pending application of Oscar J. Sundstrand, Serial No. 581,800, filed December 18, 1931, and 45 the United States patents of Oscar J. Sundstrand, No. 2,060,954, issued November 17, 1936 and No. 2,091,339, issued August 31, 1937.

It will be understood, of course, that in using the present invention with the mechanisms of the 50 above disclosures, parts may be omitted from these disclosures wherever the function or operation of those parts is inconsistent with or unnecessary to the operation of the present invention.

The mechanism provided for automatically 55

opening and closing front feed bail 6 is operated by lateral movement of the carriage, the bail being closed when the carriage moves from right to left on its working stroke, and opened when the carriage moves from left to right on its return stroke. The mechanism for operating the front feed bail in these movements includes a cam member 17 (Figures 2, 3 and 4) secured on a bracket 18 by a screw 21. Bracket 18 supports a rod 22 (Figure 6) extending between its side flanges and secured thereto by screws 23. Another rod 24 extends between the side flanges of bracket 18 above rod 22. A spring 25 is connected to rod 24 and to a rod 26 supported in flanges on each side of a plate 27 secured to the machine frame. This construction enables bracket 18 to be pivoted about rod 22, to move the upper end of the bracket away from the machine, as illustrated by the dot and dash lines in Figure 4. In swinging the upper end of the bracket away from the machine, it is first raised slightly against the tension of spring 25 to lift rod 24 out of notches 28 in plate 27, slots 31 in plate 27 allowing a corresponding rise of rod 22. This pivotal movement of bracket 18 serves no useful purpose in the operation of the front feed bail opening and closing mechanism but is necessary to provide clearance for removing a detachable control plate 32 that supports control magazines 33.

30 Cam member 17 lies in the path of a roller 34 (Figures 4 and 5) rotatable on a screw 35 extending through two clamping plates 36 and 37 and threaded into a thumb nut 38. Clamping plates 36 and 37 embrace two rods 41 extending laterally of the machine, as shown in Figure 2. Referring to Figure 5, it will be noted that tightening of thumb nut 38, assisted by a shoulder near the head of screw 35 bearing against clamping plate 36, causes clamping plates 36 and 37 to tighten against rods 41 to hold the unit against movement along the rods.

Rods 41 are secured at each end to levers 42 (Figure 2) pivoted on screws 43 at each end of the carriage. One or more clamps 44 are secured 45 to the two rods 41 to provide additional rigidity to the swinging frame structure composed of parts 34 to 42.

At the right side of the carriage a pitman 45 (Figures 2 and 7) is pivoted at 46 to the lower 50 end of lever 42 and rests, near its forward end, in a shallow groove in a stud 47 secured in the carriage side wall 4. A tension lever 48 is likewise pivoted to the carriage side wall at 51 and rests on a stud 52 on pitman 45. A spring 53 is connected to the rear end of lever 48 and to the carriage side wall. The normal position of these parts is illustrated in Figure 7 where roller 34 is in the vertical plane of pivot screws 43.

The forward end of pitman 45 is provided with 60 two depending lugs 54 and 55 adapted to co-act with a stud 56 on front feed bail 6. Figure 7 shows that there is sufficient clearance between lugs 54 and 55 to permit the front feed bail to be manually opened or closed, if desired.

65

Operation

Assuming that the front feed bail is closed and the carriage has completed its working stroke and is returning to its right hand position, roller 70 34 contacts cam member 17 near the end of the return stroke and moves pitman 45 forward to the position shown in Figure 8, opening the bail 6. The carriage continues traveling for a short distance, whereupon spring 53, through a cam 75 surface 57 on lever 48, together with the weight of

the swinging assembly 34 to 42, returns pitman 45 and the swinging assembly to the normal position shown in Figure 7. The space between lugs 54 and 55 is sufficient to allow the swinging assembly to return to normal and still leave the 5 front feed bail 6 open.

The operator then inserts a new work sheet and begins to operate the machine. In the type of work for which the present structure is adapted, the first printed entry is made only on the 10 work sheet inserted from the rear of the platen and not on the work sheet inserted from the front thereof. Therefore, it is not necessary that the front feed bail be closed during this operation. At the completion of the operation the carriage 15 tabulates, as explained in the above mentioned application Serial No. 581,800, during which tabulation roller 34 contacts the rear edge of cam member 17, moving the swinging assembly 20 rearwardly to the position shown in Figure 9, lug 54 contacting stud 56 and closing the front feed bail. After roller 34 passes beyond cam member 17 a cam surface 58 on lever 48, accompanied by the weight of the swinging assembly, returns the assembly to normal position shown in Figure 7.

Modification

Figures 10 to 12 show a modified form of the invention that is used where it is desired to open 30 the front feed bail automatically but not to close it automatically. In this form of the invention, pitman 45a is provided with a lug 55a, but no lug corresponding to lug 54 (Figure 7). Therefore, movement of roller 34 forward, during the return 35 stroke of the carriage, to the position shown in Figure 11, opens the front feed bail, but movement of roller 34 rearward, during the working stroke of the carriage, to the position shown in Figure 9, will have no effect on the bail. Figure 40 10 illustrates the roller moved to a position where it is entirely disabled. This is accomplished by the operator manually moving pitman 45a to its extreme rearward position where stud 52 engages a deep notch 61 in link 48a. The tension of spring 45 53 is sufficient to hold the stud in engagement with the notch.

If, in the use of this modified form of the invention, it is desired to have the front feed bail open near the end of the working stroke of the 50 carriage, instead of on the return stroke, cam 17 would be adjusted to the position shown by the dot and dash lines in Figure 3. When in this position, the cam member moves roller 34 forward during the last increment of travel of the carriage in its working stroke, to open the bail. This is often desirable as it gives the operator an opportunity to change the front fed work sheets during the return movement of the carriage.

For types of work requiring that the front 60 feed bail be opened twice during each excursion of the carriage it is apparent that it is only necessary to provide an additional roller 34 at the desired location on rods 41.

While the form of mechanism herein shown 65 and described is admirably adapted to fulfill the objects primarily stated, it is to be understood that it is not intended to confine the invention to the one form of embodiment herein disclosed for it is susceptible of embodiment in various forms 70 all coming within the scope of the claims which follow.

What is claimed is:

1. In a machine of the class described having a traveling paper carriage, a platen and front 75

- feed mechanism, a cam member supported on the machine frame, an engaging member supported on the carriage frame for movement in one direction by the cam member when the carriage moves 5 from left to right, and for movement in the opposite direction by the cam member when the carriage moves from right to left, and a connection between the engaging member and the front feed mechanism for opening and closing the mechanism during the movements of the engaging member.
2. In a machine of the class described having a traveling paper carriage, a platen thereon, pressure rolls bearing against the front of the platen, 15 an adjustable support for the pressure rolls, a cam member and a member operated thereby, one of said members being mounted on the machine frame and the other member being supported for lateral movement with the carriage and moved by 20 said one member in two directions during travel of the carriage, and a connection between the said other member and the pressure rolls for moving the pressure rolls toward and away from the platen.
- 25 3. In a machine of the class described having a traveling paper carriage, a platen thereon, front feed mechanism thereon adapted to be opened and closed, and means situated between the carriage and a stationary part of the machine for 30 opening the front feed mechanism during travel of the carriage in one direction and for closing the front feed mechanism during travel of the carriage in the opposite direction.
4. In a machine of the class described having 35 a traveling paper carriage, a platen thereon, a front feed mechanism thereon, a member suspended on a swinging frame, a connection between the swinging frame and the front feed mechanism, and a second member on a stationary 40 part of the machine lying in the path of the said member and adapted to move the said member in one direction during the return stroke of the carriage and in the opposite direction during the working stroke of the carriage to open and close 45 the front feed mechanism.
5. In a machine of the class described having a traveling paper carriage, a roller platen and front feed mechanism thereon, and means for automatically opening and closing the front feed 50 mechanism during travel of the carriage, the said means being so constructed that the front feed mechanism can be manually opened or closed while the carriage is at rest in any columnar position.
- 55 6. In a machine of the class described having a traveling paper carriage, a roller platen and front feed mechanism thereon, means movable in one direction for automatically opening the front feed mechanism during lateral travel of the carriage in one direction and movable in the opposite direction for automatically closing the front feed mechanism during lateral travel of the carriage in the opposite direction, and means 60 for returning the first mentioned means to normal position following each of the said movements thereof.
7. In a machine of the class described having a traveling paper carriage including a roller platen and a front feed mechanism, means for automatically operating the front feed mechanism during travel of the carriage, and means for returning a part of the operating means to initial position while the front feed mechanism remains in operated position.
8. In a machine of the class described having a traveling paper carriage including a roller platen and a front feed mechanism, a camming means for automatically operating the front feed mechanism during travel of the carriage in one direction, and means for reversing the operation of the operating means whereby it again operates the front feed mechanism during travel of the carriage in the other direction.
9. In a machine of the class described having a traveling paper carriage including a roller platen and a front feed mechanism, means for automatically operating the front feed mechanism at a predetermined point during travel of the carriage in one direction, and means whereby a portion of the operating means may be adjusted to cause the operating means to similarly operate the front feed mechanism at the same point during travel of the carriage in the other direction.
10. In a machine of the class described having a traveling paper carriage, a platen and front feed mechanism, a connection between the carriage and the machine frame including a cam member, a roller, and a connection between these parts and the front feed mechanism, the parts being so arranged that the said connection is moved in one direction by the cam member and roller to open the front feed mechanism when the carriage travels in one direction, and is moved in another direction by the cam member and roller to close the front feed mechanism when the carriage travels in the opposite direction.
11. In a machine of the class described having a traveling paper carriage, a platen and front feed pressure rolls, means operated by an element on the machine frame during travel of the carriage in one direction for moving the pressure rolls away from the platen, and operated by said element during travel of the carriage in the opposite direction for moving the pressure rolls toward the platen.
12. In a machine of the class described, a traveling paper carriage, a front feed mechanism thereon, and a cam member for opening and closing the front feed mechanism during travel of the carriage.
13. In a machine of the class described, a traveling paper carriage, a front feed mechanism thereon, a cam member on the machine frame, and connections between the cam member and the front feed mechanism, and operated by the cam member, for opening and closing the front feed mechanism during travel of the carriage.

WALTER A. ANDERSON. 65
